US00D774017S

(12) **United States Design Patent** (10) **Patent No.:** **US D774,017 S**
Ahn et al. (45) **Date of Patent:** **** Dec. 13, 2016**

(54) **WIRELESS HEADSET**

(71) Applicant: **LG ELECTRONICS INC.**, Seoul (KR)

(72) Inventors: **Yooshin Ahn**, Seoul (KR); **Seungbeom Park**, Seoul (KR)

(73) Assignee: **LG ELECTRONICS INC.**, Seoul (KR)

(**) Term: **15 Years**

(21) Appl. No.: **29/535,584**

(22) Filed: **Aug. 7, 2015**

(30) **Foreign Application Priority Data**

Feb. 9, 2015 (KR) 30-2015-0006877

(51) **LOC (10) Cl.** **14-01**

(52) **U.S. Cl.**

USPC **D14/205**

(58) **Field of Classification Search**

(57) **CLAIM**

The ornamental design for wireless headset, as shown and described.

DESCRIPTION

FIG. 1 is a perspective view of a wireless headset showing our new design;

FIG. 2 is a front view thereof;

FIG. 3 is a rear view thereof;

FIG. 4 is a left side view thereof where the right side view is a mirror image;

FIG. 5 is a top plan view thereof;

FIG. 6 is a bottom plan view thereof;

FIG. 7 is a reference view thereof showing the state that the earphone part and the main body can be detached; and, FIG. 8 is a reference view thereof showing an example of the usage of the subject design.

The broken lines depict portions of the wireless headset that form no part of the claimed design.

1 Claim, 7 Drawing Sheets
